UNITED STATES PATENT OFFICE.

THEODOR BÄSSLER, OF NEUSS, GERMANY.

PULP-ENGINE.

SPECIFICATION forming part of Letters Patent No. 716,172, dated December 16, 1902.

Application filed November 8, 1901. Serial No. 81,526. (No model.)

To all whom it may concern:

Be it known that I, THEODOR BÄSSLER, a citizen of Germany, and a resident of Neuss, Rhenish Prussia, Germany, have invented 5 certain new and useful Improvements in Pulp-Engines, of which the following is a specification.

This invention relates to a pulp-engine which will effect a thorough trituration of the 10 mass.

The accompanying drawing is a plan, partly in section, of my improved pulp-engine.

The letter *t* represents a horizontal casing having contracted ends *t'*, which are coupled 15 to a horizontal tube *r*, so as to form a continuous horizontal passage. At the center the casing *t* is enlarged to form a squared chamber which is wider than tube *r* and accommodates the horizontally-hung triturating-roller 20 *w*. The shaft *w*³ of this roller extending across tube *r* turns in bearings *w'* and is driven from pulley *w*². The squared chamber of casing *t* is provided with two tapering or coniform ends which merge at their apex 25 into the inwardly-turned contracted necks *t'*. The pulp moved forward by roller *w* in a horizontal direction will be gradually compressed within the contracted necks and will be forced rapidly through the comparatively narrow

tube *r* to become thoroughly mixed and uniformly triturated. The casing *t*, as well as the return-tube *r*, are arranged in a horizontal plane, so that the pulp need not be lifted during trituration and deposits will not accumulate in the tube. 30

If desired, the inner face of the tube *r* may be threaded or provided with inclined blades to turn the pulp. It may also be provided with a rotatable stirrer or a screw conveyer to advance and simultaneously stir the mass. 40 Hand-holes for facilitating the cleaning or inspection of the tube may also be provided. 35

What I claim is—

In a pulp-engine, a horizontal casing having a squared chamber with coniform ends and 45 inwardly-turned contracted necks, combined with a horizontal tube in the same horizontal plane with the chamber and connecting the contracted necks, and with a triturating-roller within the chamber, substantially as speci- 50 fied.

Signed by me at Düsseldorf, Germany, this 29th day of October, 1901.

THEODOR BÄSSLER.
